TOBACCO STEMMING MACHINE
CONSTRUCTIONRupert E. Rundell, Rockville Centre, N. Y., as-
signor to American Machine & Foundry Com-
pany, a corporation of New Jersey

Application October 5, 1935, Serial No. 43,662

12 Claims. (Cl. 131—57)

This invention relates to improvements in tobacco stemming machines, more particularly to machines of the type described in my prior Patent No. 1,968,098, granted July 31, 1934. The main object of the invention is to prevent overlapping of the gripper jaws due to side play which would prevent closure thereof and result in drop leaves, and to this end each gripper on the conveyor chain is provided with lugs which abut similar lugs on adjacent grippers. A further object is to provide novel means for simultaneously adjusting the conveyor drive sprocket and the cam which opens the gripper jaws to release the stripped stems, in such a manner that the same relationship of said cam and the grippers is always maintained. Another object of the invention is the provision of a positive drive for the stem ejector rolls. With these and other objects not specifically mentioned in view the invention consists in certain constructions and combinations hereinafter fully described and then specifically set forth in the claims hereunto appended.

In the accompanying drawings which form a part of this specification and in which like characters of reference indicate the same or like parts:

Fig. 1 is a partial side elevation of the ejector end of a stemming machine equipped with the improved grippers, the novel means for adjusting the conveyor drive sprocket and the cam and the positive drive for the stem ejector rolls;

Fig. 2 is a detail top view of the conveyor drive sprocket, showing the improved means for adjusting the same with the cam;

Fig. 3 is a sectional plan view of the positive drive for the stem ejector rollers, taken on line 3—3 of Fig. 1;

Fig. 4 is a cross-section taken through the conveyor drive sprocket; and

Fig. 5 is a detail side view of the idler roller of the conveyor.

Generally stated in the embodiments of the various features of the invention herein illustrated, there are provided a driving sprocket, an endless chain trained over said sprocket, sets of opposed grippers pivotally mounted on said chain, a cam for opening said grippers to release stems gripped therebetween, a support for said sprocket and cam, and means for adjusting said support without rotating it to preserve the same relationship of the cam to the grippers. In the best constructions contemplated each gripper is provided with lugs abutting similar lugs on adjacent grippers and thereby preventing overlapping of

adjacent grippers, and there is also provided a set of positively driven stem ejector rolls to remove any stems adhering to the grippers after they have been opened. The various constructions shown herein may be widely varied in construction for they are but certain of many possible concrete embodiments of the same. The invention, therefore, is not to be restricted to the details illustrated and described nor to the particular embodiments chosen as illustrative of the invention.

Referring to the drawings, wherein is shown one embodiment of the various features comprising the invention, the main shaft 10 of the stemming machine carries a bevel gear 11 meshing 15 with a bevel gear 12 mounted on the lower end of a vertical shaft 13. Shaft 13, at its lower end, is journaled in a bearing bracket 14, and its upper portion is supported in bearings provided in a gear housing 15 and its cover 16. The gear housing 15 has a well 17 and is formed integrally on the side of a hollow casting 15a supported by a pair of standards 18 which are fastened at their lower ends to upright lugs of a pedestal 19. The latter is attached to the frame 20 of the machine 25 and is provided with a bearing 21 which supports one end of the shaft 10.

On the upper end of the vertical shaft 13 is fastened a worm 22 which meshes with a worm wheel 23 mounted on a shaft 24 journaled in the sides of the well 17. Also mounted on shaft 24 is a pinion 25 which drives a gear 26 mounted on a sprocket shaft 27 (Fig. 4). The shaft 27, which is supported in one of the projecting arms 28 of the E-shaped support 29 (Fig. 2) carries one end 35 of the hub of a double sprocket 27a which is mounted at its other end on a shaft 27b journaled in the other arm 28. The support 29 is provided with studs 30 on which a pair of links 31 are loosely mounted, the links 31 being pivoted 40 on studs 32 set in the sides of the casting 15a (Figs. 1 and 2). A gear-guard 33, which is loosely mounted on the shaft 24 in parallelism with one link 31, is pivotally mounted on the shaft 27 and encloses the gears 25 and 26. A 45 link 34 parallel to the other link 31 is pivoted on a shaft 24a carried by the other standard 15 and loosely mounted on the shaft 27b.

The support 29 (Fig. 2) is provided with a central lug 35 to which is fastened the base 36 of a stationary cam 37 underneath the hub of the sprocket 27a. On a bracket 38 attached to one of the arms 28 of support 29 is supported a shaft 39 which carries a wiper brush or wheel 40 formed of felt or other suitable material.

An adjusting screw 41, which bears against the support 29, is carried by a lug 42 of the casting 15a. The screw 41 is provided to permit adjustment of the tension of conveyor chain 45 which 5 runs over the double sprocket 27a. Parallel motion is imparted to the support 29 by turning the screw 41; and a similar movement is thus imparted to the shafts 27 and 27b of the sprocket 27a and the cam 37 which are carried by the 10 support, wherefore the said members are moved with a translatory motion during the adjustment.

The conveyor chain (Figs. 1 and 2) is made up of links 45 joined by pins 46 carrying rollers 47 which ride on rails 48 (Fig. 1) and thus support the chain while the stems are being stripped by stemming mechanism which need not be shown herein since it is fully disclosed in my prior patent identified above. The links 45 carry pins 49 (Fig. 2) on which pairs of coacting grippers 50 and 51 are pivoted. Each gripper carries on its inner end a cam roller 52, the inner ends of each pair of grippers being normally held apart by springs 53 which are interposed therebetween, so that their other ends, which form the gripper 25 jaws 54, will be held tightly closed on a stem placed between them.

The butts of leaves to be stemmed are inserted between the grippers of the chain, in the same manner as described in the above mentioned patent and the leaves are then carried through the cleaning and stripping units of the machine. The stripped stems S (Fig. 1) are then advanced towards the sprocket 27a. As each pair of grippers of the conveyor chain turns around the 35 sprocket 27a (Figs. 1 and 2) the rollers 52 engage the inner face of the cam 37, which compresses the spring 53 and thus opens the gripper jaws 54, allowing the stripped stems to fall into a chute leading to a suitable receptacle (not 40 shown). If a stripped stem S should stick to the opened jaws it will then be drawn between two oppositely revolving rolls 60 (Fig. 3) which will nip the stem, and eject it downwardly. The stem ejector rolls 60 may be formed of rubber or 45 other suitable resilient material and have their forward ends beveled to freely admit the stems therebetween.

The rolls 60 (Figs. 1 and 3) are positively driven from a bevel gear 61 mounted on the shaft 13, the 50 gear 61 meshing with a bevel gear 62 mounted on a shaft 63. To the end of shaft 63 is fixed a sprocket 64 which, through a chain 65, drives a sprocket 66 mounted on a shaft 67. A gear 68, fixed on shaft 67, meshes with a gear 69 fastened 55 on shaft 70, thus revolving in the opposite directions the rolls 60 which are mounted on the ends of shafts 67 and 70. It should be noted that this positive drive for the stem ejector rolls assures removal of any stems adhering to the opened 60 grippers and that stems must be pulled with an appreciable force for removal, especially whenever the machine is stopped with any stems gripped between the jaws.

While the cleared gripper jaws are still held 65 open by the cam 37, they are carried over the side faces of the wiper wheel 40 which removes all adhering tobacco scraps, gum and other matter which might otherwise prevent the grippers from positively gripping the next stem or cause 70 slippage of the same. The wiper wheel 40 mounted on the shaft 39 is driven by means of a chain 71 which runs over sprockets 72 and 73 (Figs. 1 and 2).

As the successive links of the conveyor chain 75 move out of engagement with the sprocket 27a,

each pair of grippers 50 and 51 thereon is swung toward the preceding pair of grippers. To overcome any possibility of the gripper jaws 54 overlapping one another, the grippers 50 and 51 (Fig. 1) are provided with guide lugs 74 which abut similar lugs on the adjacent grippers, the abutting surfaces being parallel to the opening and closing movement of the grippers, to assure a clearance between the jaws 54, when they are successively closed on the butts of the leaves which 10 are to be stemmed.

This feature is of great importance since wear or faulty workmanship would otherwise permit such overlapping when the links supporting the same leave the idler roller 100 of the conveyor 15 chain (Fig. 5), the grippers being opened by engagement of their cam rollers with a stationary cam 101 which permits them to close and grip the butts of the leaves inserted therebetween shortly after they leave the idler roller. Since the construction of this end of the machine is similar to that shown in my prior patent mentioned above, further description thereof is deemed unnecessary.

What is claimed is:

1. In a tobacco stemming machine, the combination with a driving sprocket, of an endless conveyor chain trained over said sprocket, a support for said sprocket, means for adjusting said support with a translatory movement, in 30 substantial alignment with the major axis of said chain, and gearing for driving said sprocket in every adjusted position thereof.

2. In a tobacco stemming machine, the combination with a driving sprocket, of an endless conveyor chain trained over said sprocket, a support for said sprocket, means for adjusting said support with a translatory movement, in substantial alignment with the major axis of said chain, said adjusting means including pivoted 40 parallel arms, links by which said arms are pivotally connected to said support, and an adjusting screw engaging said support, and gearing for driving said sprocket in every adjusted position thereof.

3. In a tobacco stemming machine, the combination with a driving sprocket, of an endless conveyor chain trained over said sprocket, a support for said sprocket, means for adjusting said support with a translatory movement, gearing 50 for driving said sprocket in any adjusted position thereof, said means including pivoted parallel arms pivotally connected to said support, and said gearing including a shaft connecting said support to one of said arms, said sprocket being 55 carried by said shaft, a pinion concentric with the pivot of the arm connected to said shaft, and a gear mounted on said shaft and driven from said pinion.

4. In a tobacco stemming machine, the combination with a driving sprocket, of an endless chain trained over said sprocket, sets of opposed grippers pivotally mounted on said chain and coacting to grip the stem butts of tobacco and transport the same, a cam arranged to engage 65 said sets of grippers successively and open the same to release the leaves, a support for said sprocket and cam, and means for adjusting said support and cam with a translatory movement into adjusted position and to maintain said cam 70 always in the same relative operative position with respect to said gripper sets.

5. In a tobacco stemming machine, the combination with a driving sprocket, of an endless chain trained over said sprocket, sets of opposed 75

grippers pivotally mounted on said chain and coacting to grip the stem butts of tobacco and transport the same, a cam arranged to engage said sets of grippers successively and open the 5 same to release the leaves, a support for said sprocket and cam, and means for adjusting said support and cam with a translatory movement to adjusted position, said means including pivoted parallel arms pivotally connected to said sup- 10 port.

6. In a tobacco stemming machine, the combination with a driving sprocket, of an endless chain trained over said sprocket, sets of opposed grippers pivotally mounted on said chain and 15 coacting to grip the stem butts of tobacco and transport the same, a cam arranged to engage said sets of grippers successively and open the same to release the leaves, a support for said sprocket and cam, means for adjusting said sup- 20 port without rotating it to maintain said cam always in the same relative operative position with respect to said grippers, and gearing for driving said sprocket in any adjusted position thereof.

7. In a tobacco stemming machine, the combination with a driving sprocket, of an endless chain trained over said sprocket, sets of opposed grippers pivotally mounted on said chain and coacting to grip the stem butts of tobacco and 30 transport the same, a cam arranged to engage said sets of grippers successively and open the same to release the leaves, a support for said sprocket and cam, means for adjusting said sup- 35 port without rotating it to maintain said cam at any adjusted position in the same relative operative relationship with said grippers, said means including pivoted parallel arms pivotally connected to said support, and a rotary cleaner member adapted to engage and clean the inner faces 40 of the opened grippers, and gearing for rotating said member; said gearing including a shaft on which said member is mounted and by which it is connected with one of said arms, a sprocket carried by said shaft, a sprocket concentric with 45 the driving sprocket, shaft connections between said concentric sprockets, and a sprocket chain connecting the sprocket concentric with the driving shaft to the sprocket on the shaft carrying said rotary cleaning member.

8. In a tobacco stemming machine, the combination with a driving sprocket, of an endless chain trained over said sprocket, and sets of opposed spring-pressed grippers pivotally mounted on said chain and coacting to grip the stem 50 butts of tobacco leaves, each of said grippers being provided with projecting lugs arranged to abut

lugs on the adjacent grippers and thereby prevent overlapping of adjacent grippers.

9. In a tobacco stemming machine, the combination with a driving sprocket, of an endless chain trained over said sprocket, and sets of opposed spring-pressed grippers pivotally mounted on said chain and coacting to grip the stem butts of tobacco leaves, each of said grippers being provided with projecting lugs arranged to abut lugs on the adjacent grippers and thereby 10 prevent overlapping of adjacent grippers, adjacent lugs having coacting guide surfaces parallel to the direction of opening and closing movement of said grippers.

10. In a tobacco stemming machine, the combination with a driving sprocket, of an endless chain trained over said sprocket, sets of opposed grippers pivotally mounted on said chain and coacting to grip the stem butts of leaves and transport the same, a cam arranged to engage 20 said sets of grippers successively and open the same to release the leaves, and a rotary cleaner arranged to engage and clean the inner faces of the opened grippers, a support for said sprocket, cam and cleaner, and means for simultaneously 25 adjusting said sprocket, cam and cleaner.

11. In a tobacco stemming machine, the combination with a driving sprocket, of an endless chain trained over said sprocket, sets of opposed grippers pivotally mounted on said chain and 30 coacting to grip the stem butts of leaves and transport the same, a cam arranged to engage said sets of grippers successively and open the same to release the leaves, and a rotary cleaner arranged to engage and clean the inner faces of 35 the opened grippers, a support for said sprocket, cam and cleaner, means for simultaneously adjusting said sprocket, cam and cleaner, said means including parallel pivoted arms pivotally connected to said support.

12. In a tobacco stemming machine, the combination with a driving sprocket, of an endless chain trained over said sprocket, sets of opposed grippers pivotally mounted on said chain and coacting to grip the stem butts of leaves and 40 transport the same, a cam arranged to engage said sets of grippers successively and open the same to release the leaves, and a rotary cleaner arranged to engage and clean the inner faces of the opened grippers, a support for said sprocket, cam and cleaner, means for simultaneously 45 adjusting said sprocket, cam and cleaner, and gearing for driving said sprocket and cleaner in any adjusted position thereof.

55
RUPERT E. RUNDELL.
